UNITED STATES PATENT OFFICE

JOHN VAN BRUNT, OF FLUSHING, NEW YORK, ASSIGNOR TO INTERNATIONAL COMBUSTION ENGINEERING CORPORATION, OF NEW YORK, N. Y., A CORPORATION OF DELAWARE

BOILER FURNACE

Application filed March 26, 1926. Serial No. 97,551.

The invention relates to boiler furnaces and is especially useful where the fuel to be burned is in finely divided form such as pulverized fuel.

5 One of the primary objects of the invention is to greatly increase the capacity of a boiler of the cross drum type without materially increasing the size of the installation.

By my invention I propose by an improved 10 novel arrangement of a cross drum boiler and a combustion chamber therefor to convert an ordinary cross drum boiler installation into a high capacity boiler installation, or construct a new installation from parts 15 heretofore used in constructing the standard forms of boilers of this class.

The invention is particularly useful, although not necessarily restricted to, the converting of sectional header substantially 20 horizontal water tube boilers in connection with which it will be described.

Other objects and advantages of my invention will be set forth hereinafter as they will be more readily understood in connection 25 with the description of the invention.

How the foregoing, together with such other objects as may be incident to my invention, are realized is illustrated in preferred form in the accompanying drawings, 30 wherein—

Fig. 1 is a vertical section through a boiler furnace embodying the preferred form of my invention;

Fig. 2 is a fragmentary section taken on 35 the line 2—2 of Fig. 1;

Fig. 3 is a modified form of downcomer connection between the cross drum and the lower drum of the tubular rear wall of the combustion chamber;

40 Fig. 4 shows a modified arrangement of the offtake; and

Fig. 5 is a cross section through several of the finned tubes which I employ to form the walls of the combustion chamber.

45 Referring now to the drawings and par-

ticularly to Fig. 1, it will be seen that I provide a combustion chamber A the walls of which are largely defined by water tubes, beneath a boiler B of the cross drum type. The boiler B comprises in general the cross drum 5; the bank of tubes 6, each vertical row of which is connected into a rear header 7 and a front header 8 said headers being of any standard form, either straight or sinuous; tubes 9, of the section of tubes C, connected between the drum 5 and the front headers 8; and finned downcomer tubes 10 connecting the drum with the rear headers 7. In addition to the tubes 9 the section of tubes C includes tubes 10 connecting the drum 5 with the front header 11 into which header the upper headers of the tubular side walls of the combustion chamber connect as will presently appear. A superheater D is located between the bank of tubes 6 and the section of tubes C.

It is to be noted that alternate headers of the front headers 8 extend above the adjacent ones whereby spaces are provided therebetween for the tubes 10 which extend from the drum 5 to the cross header 11.

The combustion chamber A comprises a front and rear tubular water wall E and F respectively, side tubular water walls G only one of which is shown in the drawings the other one being of the same construction, and top and bottom screens H and I respectively.

The rear wall F is formed of finned tubes 12 connected at their upper ends into the upper cross header 13 located adjacent the rear headers 7 of the bank of tubes 6 and at their lower ends into the lower drum 14. The front wall E is formed of finned tubes 15 one for each of the headers 8 of the bank of tubes 6 into which headers 8 they are connected at their upper ends. The tubes 15 connect at their lower ends into the cross header 16. The side walls G are formed of finned tubes 17 connected at their upper ends into the upper cross headers 18 located opposite the cross

drum boiler B and at their lower ends into the lower cross headers 19. The lower drum 14 and the headers 16 and 19 are located a sufficient distance below the cross drum boiler so as to provide an adequate combustion space. The screens H and I marginal of the top and bottom of the combustion chamber respectively are formed of spaced tubes 20 and 21, the tubes 20 of the upper screen connecting the upper header 13 of the rear wall with the front headers 8 of the bank of tubes and the tubes 21 of the lower screen connecting the lower headers 16 and 14 of the front and rear walls respectively.

15 A downcomer pipe 22 connects the cross drum 5 with the lower drum 14 of the front wall E by virtue of which and by the interconnection of the tubes of the end walls and the tubes of the top and bottom screens the circulation will be downward from the drum 5 to the drum 14 and upward thru the tubes 12 and 20 to the headers 8 and also upward thru the tubes 21 and 15 to the headers 8. In the arrangement shown in Fig. 1 it is preferable to provide one of the downcomer pipes at each end of the drum 5 and the drum 14. In Fig. 3 I have shown a modified form of downcomer connection in which a plurality of small diameter pipes 22a are employed. The circulation of the cross drum boiler B is from the rear headers 7 to the front headers 8 by virtue of the downcomer connections 10 from which it will be seen that the circulation of both the boiler and the above mentioned tubular screens is toward the front headers 8 of the boiler B. The circulation thru the tubes of the section C is from the front headers 8 and 11 to the cross drum 5.

In connection with the side walls G it is pointed out that the lower headers thereof are connected into the lower drum 14 of the rear wall and that the upper headers 18 thereof are connected into the front header 11 of the section C. Hence the circulation is upward in the side walls G and from the header 11 to the cross drum 5 in the tubes 10.

The fuel and combustion air are introduced to the combustion chamber in a manner to produce violent and intense combustion by means of the burner nozzles 23 located at the four corners of the boiler furnace. Combustion air is supplied around the burners 23 from an air heater (not shown) located in the stack or offtake 24 which offtake is shown in Fig. 1 as being located above the boiler B and above the economizer section C. A conduit 25 is led from the air heater to the casing 26 thru the medium of which the air is supplied around the burners. The preheated combustion air increases the furnace temperature head, and since the combustion chamber is defined by water tubes exposed to radiant heat there is a very rapid transfer of heat.

The products of combustion are drawn thru the top screen H and the bank of tubes 6,

thence thru the superheater, thence thru the integral section C and finally thru the air preheater in the stack or offtake. Thus it will be seen that these parts are subjected to the hot gases, the top screen H however being exposed to radiant heat.

In Fig. 4 I have shown a modification in which the offtake 24a is located directly beneath the cross drum 5.

From the foregoing it will be apparent that I am enabled to greatly increase the capacity of a cross drum boiler installation by converting it into a boiler furnace, and this without materially increasing the size of the original installation.

While I have shown and described my invention as converting a Babcock and Wilcox cross drum boiler, it is to be understood that the advantages to be had through the practice of my invention may be had by converting other boilers of this general class.

I claim:—

1. A boiler furnace comprising in combination a boiler of the cross drum type having the usual drum and a bank of substantially horizontal tubes and their headers, a combustion chamber beneath said boiler; means for introducing fuel and air under conditions to produce violent and intense combustion, an offtake above said bank of tubes for drawing off the products of combustion; said combustion chamber including side walls formed of water tubes and headers at each end into which they are connected, a front wall formed of upright water tubes and a header at their lower ends into which they are connected and being connected at their upper ends to the front headers of aforesaid bank of tubes, a rear wall formed of upright water tubes and a drum at their lower ends and a header at their upper ends into which they are connected, spaced tubes marginal of the top of said combustion chamber connecting the upper header of the rear wall tubes to the front headers of the bank of tubes and spaced tubes marginal of the bottom of said combustion chamber connecting the lower header of the front wall tubes with the lower drum of the rear wall tubes; a downcomer connection between the drum of the cross drum boiler and the lower drum of the rear wall; an upcomer connection between the headers at one end of the side wall tubes and the drum; and means for connecting the headers at the other end of the side wall tubes to the lower drum of the rear wall tubes.

2. A boiler furnace comprising in combination a boiler of the cross drum type having a bank of substantially horizontal tubes each vertical row of which is connected into a front and rear header, a combustion chamber therebelow largely defined by tubular water walls comprising a front wall formed of finned tubes and a header below the aforesaid front headers said tubes connecting said lower

- header and said front headers, a rear wall formed of finned tubes, an upper cross header therefor adjacent the aforesaid rear headers, and a lower cross drum therefor, side walls 5 formed of finned tubes, upper cross headers therefor opposite the cross drum boiler and lower cross headers therefor, and a bottom screen of spaced tubes connecting the lower header of the front wall with the lower drum 10 of the rear wall, means connecting the upper header of the rear wall with the front headers of the cross drum boiler, a downcomer connection from the cross drum boiler to said lower drum and an upcomer connection from 15 the upper headers of the side walls to the boiler, the lower headers of the side walls being connected with said drum, and means for introducing fuel to be burned in suspension in said combustion chamber. 20 3. The combination with a boiler of the cross drum type having the usual drum and a bank of substantially horizontal tubes, each vertical row of which is connected into a front and rear header, alternate headers of said 25 front headers extending upwardly beyond the adjacent ones, water tubes connecting the cross drum with said front headers, a water wall, a cross header, said water wall being connected to said cross header, and water tubes 30 connecting the cross drum with the cross header said tubes passing thru the spaces between said alternate upwardly extending headers above said adjacent headers. 4. A boiler furnace comprising, in combination, a boiler of the cross drum type having the usual drum and a bank of substantially horizontal tubes and their headers, a combustion chamber beneath said cross drum boiler, said combustion chamber including end 35 tubular water walls and spaced water tubes marginal of the top and bottom thereof, header means for connecting the bottom tubes with the tubes of the end water walls, header means for connecting the top tubes at one end 40 with the tubes of one end wall, said top tubes being at their other ends connected to the cross drum boiler, and means for introducing fuel to be burned in suspension in said combustion chamber. 45 5. A boiler furnace comprising, in combination, a boiler of the cross drum type having the usual drum and a bank of substantially horizontal tubes and their headers, a combustion chamber beneath said cross drum boiler, said combustion chamber including side and end tubular water walls and spaced water tubes marginal of the top and bottom thereof, header means for connecting the bottom tubes with the tubes of the end water walls, 50 header means for connecting the top tubes at one end with the tubes of one end wall, said top tubes at their other ends being connected to the cross drum boiler and the tubes of the other end wall being connected to the cross 55 drum boiler, header means into which the tubes of the side walls are connected, means connecting the last named header means at one end of said side wall tubes into the header means of one of the end walls, means for connecting the header means at the other end of 70 said side wall tubes to the cross drum boiler, and means for introducing fuel to be burned in suspension in said combustion chamber. 75 In testimony whereof, I have hereunto signed my name.
